(57) **CLAIM**

The ornamental design for a window rain guard and wind deflector with bubble design, as shown and described.

DESCRIPTION

FIG. 1 is a front elevational view of my new design for a window rain guard and wind deflector with bubble design; FIG. 2 is a right side elevational view thereof;

FIG. 3 is a rear elevational view thereof;

FIG. 4 is a left side elevational view thereof;

FIG. 5 is a top plan view, the bottom plan view being a mirror image thereof;

FIG. 6 is a front perspective view thereof, shown with unclaimed environmental structure; and,

FIG. 7 is a rear perspective view thereof.

The broken lines in FIG. 6 depict unclaimed environmental subject matter that forms no part of the claimed design.
